[57] CLAIM

The ornamental design for a water display device, as shown and described.

DESCRIPTION

FIG. 1 is a perspective view of the display device installed within the corner of a room with the wall depicted in phantom and forming no part of the claimed design, most of the piping is installed behind the wall and is therefore not visible.

FIG. 2 is a perspective view of the entire display device.

FIG. 3 is a top view of the display device.

FIG. 4 is a bottom view of the display device.

FIG. 5 is a right side view of the display device.

FIG. 6 is a rear view of the display device.

FIG. 7 is a left side view of the display device; and,

FIG. 8 is a front view of the display device.
